PROCESS FOR PREPARING PERFLUOROALKANE-DIOIC ACIDS
John J. Drysdale, Wilmington, Del., assignor to E. I. du Pont de Nemours and Company, Wilmington, Del., a corporation of Delaware
No Drawing. Filed May 15, 1961, Ser. No. 109,822
7 Claims. (Cl. 260—537)

This invention relates to a process for preparing perfluoroalkanedioic acids and more particularly for preparing such acids by the hydrolysis of certain bis(alkylthio)-perfluoroalkanes.

Perfluorodicarboxylic acids of structure

are a valuable series of known compounds. Those, wherein m is greater than one, are known to be useful intermediates for the preparation of polyester lubricants and the like which are highly stable thermally and oxidatively (O'Brian et al., W.A.D.C., Tech. Rept. No. 56-11, A.D. 110674). Several methods are known for preparing perfluorodicarboxylic acids but they are, in general, rather poor, requiring starting materials which are not readily obtained or involving reactions which give poor yields at best.

It is an object of this invention to provide an improved process for preparing perfluoroalkanedioic acids. Another object is to provide a process for preparing perfluoroalkanedioic acids in high yields from readily available starting materials. A further object is to provide a process which is simple and readily carried out and produces the perfluoroalkanedioic acids in a more economical manner. Another object is to advance the art. Still other objects will appear hereinafter.

The above and other objects may be accomplished in accordance with this invention which comprises heating a bis(alkylthio)perfluoroalkane of the formula

wherein R is an alkyl radical of 1 to 6 carbon atoms and n is an integer of from 2 to 20 with from about 1 to about 4 parts by weight of concentrated sulfuric acid of from about 80% to 100% strength at a temperature of from about 100° C. to about 350° C., and recovering the perfluoroalkanedioic acid from the reaction mixture.

By such process, perfluoroalkanedioic acids are readily prepared in high yields in a single reaction step. The bis(alkylthio)perfluoroalkanes are readily available materials known to the art. The process is easy to operate and control and economically attractive.

The bis(alkylthio)perfluoroalkanes which may be employed in the process of this invention have the formula $\text{RS}(\text{CF}_2\text{CF}_2)_n\text{SR}$ wherein R is an alkyl radical of 1 to 6 carbon atoms and n is an integer of from 2 to 20. While R may be almost any saturated alkyl radical, it is desired (primarily for economical reasons) that the alkyl radicals contain not more than 6 carbon atoms, and preferably methyl. The bis(alkylthio)perfluoroalkanes employed in this invention conveniently are prepared by the method described by Hanford in U.S. Patent 2,443,003, and particularly in Example 2 thereof. By such process, there is produced a series of compounds of the formula $\text{RS}(\text{CF}_2\text{CF}_2)_n\text{SR}$ wherein n has a series of in-

2

tegral values of 1 to 25 or perhaps greater. Representative bis(alkylthio)perfluoroalkanes which are suitable for the purpose of this invention are: 1,4-bis(methylthio)-perfluorobutane ($\text{CH}_3\text{S}(\text{CF}_2)_4\text{SCH}_3$), 1,6 - bis(methylthio)perfluorohexane ($\text{CH}_3\text{S}(\text{CF}_2)_6\text{SCH}_3$), 1,8-bis(methylthio)perfluoroctane ($\text{CH}_3\text{S}(\text{CF}_2)_8\text{SCH}_3$), 1,10 - bis(methylthio)perfluorodecane ($\text{CH}_3\text{S}(\text{CF}_2)_{10}\text{SCH}_3$), 1,12-bis(methylthio)perfluorododecane ($\text{CH}_3\text{S}(\text{CF}_2)_{12}\text{SCH}_3$), 1,14-bis(methylthio)perfluorotetradecane

1,15 - bis(methylthio)perfluorohexadecane
$$(\text{CH}_3\text{S}(\text{CF}_2)_{16}\text{SCH}_3)$$

and 1,18-bis(methylthio)perfluoroctadecane.

The sulfuric acid employed should have a concentration of from about 80% to 100% strength. Usually, the commercial concentrated sulfuric acid of about 95% to about 98% strength will be employed. Also, the sulfuric acid should be employed in the proportion of from about 1 to about 4 parts by weight per part of the bis(alkylthio)perfluoroalkane.

The temperature for carrying out the reaction may be from about 100° C. to about 350° C., and preferably from about 150° C. to about 175° C. The reaction time usually will vary from about 1 to about 10 hours, depending upon the particular starting material, the temperature employed, and economical factors such as the cost of more extended periods of heating and the increase in yield to be obtained thereby.

A number of methods are available for recovering the product from the reaction mixture. One method, which was employed in the examples presented herein-after and which is suitable for those acids which are reasonably soluble in dilute aqueous sulfuric acid, is to add the cooled reaction mixture to cooled water, filter the resulting aqueous solution, and then extract the dicarboxylic acid from the aqueous sulfuric acid with a suitable solvent. The perfluoroalkanedioic acids which contain up to about 12 carbon atoms are reasonably soluble in water and in dilute aqueous sulfuric acid solutions, but can be crystallized from the aqueous solutions as the dihydrates. During the reaction, certain amounts of sulfur and tarry material are formed which are insoluble in the dilute aqueous solution, and such materials and unreacted starting material are removed by filtration of the cold dilute sulfuric acid solution. The perfluoroalkanedioic acid will be extracted from the aqueous solution by a lower dialkyl ether such as diethyl ether, dipropyl ether and dibutyl ether. The extracted solvent is then evaporated to leave a residue of the perfluoroalkanedioic acid. Such perfluoroalkanedioic acid sometimes will contain a small amount of partially hydrolyzed material having the formula $\text{RS}(\text{CF}_2\text{CF}_2)_n\text{CO}_2\text{H}$ which is water soluble and is extracted with the ether. If necessary, the perfluorodialkanedioic acid may be purified by recrystallization, distillation, or the like.

When the perfluoroalkanedioic acids are insufficiently soluble in dilute aqueous sulfuric acid, i.e. contain more than 12 carbon atoms, the cooled reaction mixture can be added to cooled water and the resulting mixture made basic with alkali, such as sodium hydroxide, sodium carbonate, and the like, to form the water-soluble alkali salts. After filtering the salt solutions to remove sulfur,

tarry material and unreacted starting material, the solution can be reacidified to precipitate the perfluoroalkanedioic acid. In this case also, partially hydrolyzed material (if present) will be carried into the perfluoroalkanedioic acid, which can be further purified by recrystallization, distillation, etc.

Representative acids which may be prepared by the present process include perfluorosuccinic acid

perfluoroadipic acid ($\text{HO}_2\text{C}(\text{CF}_2)_4\text{CO}_2\text{H}$), perfluorosuberic acid ($\text{HO}_2\text{C}(\text{CF}_2)_6\text{CO}_2\text{H}$), perfluorosebatic acid ($\text{HO}_2\text{C}(\text{CF}_2)_8\text{CO}_2\text{H}$), perfluorododecanedioic acid ($\text{HO}_2\text{C}(\text{CF}_2)_{10}\text{CO}_2\text{H}$), perfluorotetradecanedioic acid ($\text{HO}_2\text{C}(\text{CF}_2)_{14}\text{CO}_2\text{H}$), and perfluoroctadecanedioic acid ($\text{HO}_2\text{C}(\text{CF}_2)_{16}\text{CO}_2\text{H}$).

In order to more clearly illustrate this invention, preferred modes of carrying it into effect, and the advantageous results to be obtained thereby, the following examples are given in which the parts and proportions are by weight except where indicated otherwise.

Example 1

1,6-bis(methylthio)perfluorohexane (29.4 parts) was heated with 40 parts of concentrated (95-98%) sulfuric acid at 150° C. for one hour. The reaction mixture was then cooled and added to ice-water. The aqueous phase was filtered to remove sulfur and tarry material, and the filtrate extracted with diethyl ether. The ether extracted with diethyl ether. The ether extract, on drying and evaporation, gave 15 parts of perfluoroadipic acid as dihydrate (62% yield). The acid was identified by converting it to several known derivatives such as the dianilinium salt, the dimethylester, the diethylester, and the diacid chloride.

Example 2

1,4-bis(methylthio)perfluorobutane (29.4 parts) was heated with 40 parts of concentrated (95-98%) sulfuric acid at 165° C. for two hours. The perfluorosuccinic acid as the dihydrate (16.8 parts, 74% yield) was isolated as in Example 1. The acid was identified via its known dianilinium salt and dimethyl ester.

Example 3

1,8-bis(methylthio)perfluoroctane (39.4 parts) was heated with stirring with 40 parts of concentrated (95-98%) sulfuric acid for one hour at 155° C. to 160° C. The perfluorosuberic acid as the dihydrate (23.4 parts, 69% yield) was isolated as in Example 1, and identified via its dianilinium salt, M.P. 183° C., and the diacid chloride, B.P. 112° C./150 mm.

Example 4

1,6-bis(methylthio)perfluorohexane (29.4 parts) was heated with 91 parts of concentrated (95-98%) sulfuric acid for six hours at 165° C. The perfluoroadipic acid as the dihydrate (19.4 parts, 78% yield) was isolated as in Example 1.

In place of the bis(methylthio)perfluoroalkanes used in the above examples, the bis(ethylthio), bis(propylthio), bis(butylthio), and the like perfluoroalkanes can be used with equal facility.

An alternate method of isolation of the perfluoroalkanedioic acids has been found which avoids the extraction with the highly flammable ethers as disclosed in the foregoing examples. In this alternate method, the reaction mixture is added to a cold mixture of water and a lower alcohol, such as methanol, ethanol, propanol and isopropanol, preferably methanol, preferably employing about a fourfold excess of alcohol over that theoretically required to convert the perfluoroalkanedioic acid to the diester. Thereby, the perfluoroalkanedioic acids are converted to their diesters, which are materially more soluble in the aqueous alcohol solutions. The cold mixture is

then filtered to remove the insoluble by-products and the filtrate heated to about 60° C. and continuously extracted with an immiscible solvent in a continuous extraction apparatus. Suitable immiscible solvents are: 1,2-dichloroethane, chloroform, methylene dichloride, trichlorotrifluoroethane, and dibutyl ether. The diester is collected by evaporation of the solvent, and separated from any partially hydrolyzed product by distillation of the residual ester. Using this method and the reaction procedure of

10 Example 2, a 67% yield of dimethyl perfluorosuccinate, B.P. 112-113° C./100 mm., is obtained. Other esters isolated in this manner are dimethyl perfluoroadipate, B.P. 120-121° C./50 mm., and diethyl perfluoroadipate, B.P. 101° C./10 mm. The esters are then hydrolyzed, 15 using dilute aqueous acid, to the acids which are collected by evaporation of the aqueous solution. For many purposes, the esters may be used in place of the acids for preparing useful derivatives.

It will be understood that the preceding examples have 20 been given for illustrative purposes solely and that this invention is not limited to the specific embodiments described therein. On the other hand, it will be readily apparent to those skilled in the art that, subject to the 25 limitations set forth in the general description, many variations can be made in the materials, proportions, and conditions employed without departing from the spirit or scope of this invention.

From the preceding description, it will be apparent that 30 the present invention provides a new and improved process for preparing perfluoroalkanedioic acids readily and economically in a single reaction step from readily available starting materials. Accordingly, it will be apparent that this invention constitutes a valuable advance in and contribution to the art.

35 The embodiments of the invention in which an exclusive property or privilege is claimed are defined as follows:

1. The process for preparing a perfluoroalkanedioic acid which comprises heating a bis(alkylthio)perfluoroalkane of the formula $\text{RS}(\text{CF}_2\text{CF}_2)_n\text{SR}$ wherein R is an alkyl radical of 1 to 6 carbon atoms and n is an integer of from 2 to 20 with from about 1 to about 4 parts by weight of concentrated sulfuric acid of from about 80% to 100% strength at a temperature of from about 100° C. to about 350° C., and recovering the perfluoroalkanedioic acid from the reaction mixture.

2. The process for preparing a perfluoroalkanedioic acid which comprises heating a bis(alkylthio)perfluoroalkane of the formula $\text{RS}(\text{CF}_2\text{CF}_2)_n\text{SR}$ wherein R is an alkyl radical of 1 to 6 carbon atoms and n is an integer of from 2 to 20 with from about 1 to about 4 parts by weight of concentrated sulfuric acid of from about 80% to 100% strength at a temperature of from about 150° C. to about 175° C., and recovering the perfluoroalkanedioic acid from the reaction mixture.

3. The process for preparing a perfluoroalkanedioic acid which comprises heating a bis(alkylthio)perfluoroalkane of the formula $\text{RS}(\text{CF}_2\text{CF}_2)_n\text{SR}$ wherein R is an alkyl radical of 1 to 6 carbon atoms and n is an integer of from 2 to 20 with from about 1 to about 4 parts by weight of concentrated sulfuric acid of from about 95% to about 98% strength at a temperature of from about 150° C. to about 175° C., and recovering the perfluoroalkanedioic acid from the reaction mixture.

4. The process for preparing a perfluoroalkanedioic acid which comprises heating a bis(alkylthio)perfluoroalkane of the formula $\text{RS}(\text{CF}_2\text{CF}_2)_n\text{SR}$ wherein R is an alkyl radical of 1 to 6 carbon atoms and n is an integer of from 2 to 6 with from about 1 to about 4 parts by weight of concentrated sulfuric acid of from about 95% to about 98% strength at a temperature of from about 150° C. to about 175° C., and recovering the perfluoroalkanedioic acid from the reaction mixture.

5. The process for preparing perfluoroadipic acid 75 which comprises heating a bis(alkylthio)perfluorohexane

5

of the formula $RS(CF_2CF_2)_3SR$ wherein R is an alkyl radical of 1 to 6 carbon atoms with from 1 to about 4 parts by weight of concentrated sulfuric acid of from about 95% to about 98% strength at a temperature of from about 150° C. to about 175° C., and recovering perfluoroadipic acid from the reaction mixture.

6. The process for preparing perfluorosuccinic acid which comprises heating a bis(alkylthio)perfluorobutane of the formula $RS(CF_2CF_2)_2SR$ wherein R is an alkyl radical of 1 to 6 carbon atoms with from 1 to about 4 parts by weight of concentrated sulfuric acid of from about 95% to about 98% strength at a temperature of

5

6

from about 150° C. to about 175° C., and recovering perfluorosuccinic acid from the reaction mixture.

7. The process for preparing perfluorosuberic acid which comprises heating a bis(alkylthio)perfluoroctane of the formula $RS(CF_2CF_2)_4SR$ wherein R is an alkyl radical of 1 to 6 carbon atoms with from 1 to about 4 parts by weight of concentrated sulfuric acid of from about 95% to about 98% strength at a temperature of from about 150° C. to about 175° C., and recovering perfluorosuberic acid from the reaction mixture.
